TURBINE DRIVEN CENTRIFUGAL MACHINE

Joseph Hertrich, Hamilton, Ohio, assignor to The Western States Machine Company, Hamilton, Ohio, a corporation of Utah

Application June 18, 1941, Serial No. 398,541

21 Claims. (Cl. 210—72)

1

This invention relates to new and useful improvements in centrifugal machines, and particularly to suspended gyratory centrifugals provided with new combinations and new features of construction which render the machines especially advantageous for use in the manufacture of sugar.

One of the objects of my invention is to provide new and improved gyratory centrifugal apparatus for sugar manufacture and the like which is well suited for operations at very high speeds, say at 2000 to 2400 R. P. M. or higher when using 40" baskets, and which is preferable in many cases to the centrifugals heretofore used for such work, in both economy of construction and operating characteristics.

Another object of my invention is to provide centrifugal apparatus of that type having new features of flexibility or variability of operation such that the machines not only may be operated at very high speeds, or at any selected speed within the capacity of an installation, but also may be accelerated in each cycle at substantially constant rates which are variable within wide limits and hence can be pre-selected and controlled at will to satisfy best the processing requirements of the particular sugar massecuite or other mixture undergoing treatment.

Another object is to provide such centrifugal apparatus which may be caused to accelerate at a predetermined substantially constant rate during a part of each cycle and to shift automatically to a different rate of acceleration at a predetermined but variable interval after the start of the cycle.

Still another object of my invention is to provide improved turbine-driven centrifugal machines for sugar manufacture or the like which embody new combinations, new features of construction and new control systems that render the machines more efficient in operation and in other respects preferable to known turbine-driven centrifugal machines.

According to the present invention I provide centrifugal apparatus which is particularly useful for very high speed centrifugal operations, as in the processing of low grade or fine-grained sugar massecuites and other mixtures that are difficult to purge effectively, wherein a suspended gyratory centrifugal basket and spindle assembly is associated with an individual impulse turbine in a new way, wherein there is a speed control system which automatically controls the top speed of the centrifugal and is subject to variation so as to change the top speed within the limits of the turbine power, and wherein there is an acceleration control system which controls the rate of acceleration of the centrifugal and which may be changed in its setting so as to vary the accelera-

2

tion and hold the same at any desired rate within wide limits.

The impulse turbine which drives the machines is preferably a hydraulic or water motor of the Pelton wheel type. This includes a wheel secured to a vertical drive shaft, a nozzle for directing a water jet against the wheel and a water housing surrounding the wheel to collect the escaping water. The centrifugal spindle and basket assembly may be of any suitable type that is suspended from a gyratory centrifugal head for gyration or swinging movement in response to unbalanced loads on the assembly. The turbine drive shaft is mounted in fixed position between spaced vertical bearings, with its lower end disposed for connection with the upper end of the centrifugal spindle through a flexible coupling in the centrifugal head. The turbine housing may provide support for these shaft bearings and may itself be mounted on conventional centrifugal framework as normally located in sugar factories; and the centrifugal head may comprise and be suspended from the usual stationary hanger which in turn is supported from the same framework as the water housing, either directly or preferably through a direct connection with the base of the housing. In this way the water housing may be made of any desired size and capacity, and it becomes practical to use for high speed centrifugals a Pelton wheel of comparatively small diameter with a large flow of water under moderately high pressure, instead of employing a larger wheel with water under higher pressure as used with known water-driven centrifugal machines.

In addition, the wheel is kept stable at all times,

so that it may operate at maximum efficiency, and the center of gyration of the centrifugal spindle

may be located at the desired point for most effi-

cient high speed operation without being limited

by its association with the water housing.

Control over the operating characteristics of the apparatus is effected through control and regulation of the turbine nozzle, which is provided with a movable needle that governs the size of the jet opening and normally is held in closed position by yieldable means such as a compression spring. The needle is movable away from closed position, to allow a jet to be forced from the nozzle opening against the buckets of the turbine wheel, when fluid pressure responsive means connected with the needle is actuated by the admission of fluid thereto under pressure. When the pressure fluid is cut off, the nozzle may be closed by the action of the compression spring.

In association with this structure, the speed control system of the apparatus comprises a speed governor connected for rotation with the centrifugal, a normally closed needle valve or the like connected with the said pressure responsive means so as to relieve the pressure of fluid there-

on when the valve is opened, and control mechanism arranged to be actuated by the governor so as to open the needle valve during the operating cycle of the machine. The governor itself preferably is mounted adjacent the upper end of the turbine drive shaft and includes an actuating member that is shifted from one position to another when the drive shaft and centrifugal have attained a predetermined speed of rotation. The actuating mechanism for the needle valve preferably is a servomotor linkage that is connected with both the valve needle and the movable needle of the turbine nozzle and arranged so that when the actuating member of the governor is shifted there will be a change in the position of this linkage, an opening of the valve to reduce the pressure of the pressure fluid and thereafter a continual action on the needle valve and the nozzle needle which will keep the centrifugal running smoothly at substantially the predetermined speed for which the governor has been set.

A characteristic of this speed control system is that the setting of the servomotor linkage determines or limits the extent of opening movement of the needle in response to fluid pressure while the machine is reaching its top speed. Control over the acceleration rate of the machine therefore may be obtained by varying the setting of the servomotor linkage, which will necessarily result in a corresponding variation in the size of the nozzle opening during acceleration and hence in the pressure or torque of the water jet on the Pelton wheel. This variation of the linkage setting may be obtained in a simple embodiment by providing the linkage with a connecting element of adjustable length, so that a change in the length of the connecting element will result in a change in the extent to which the nozzle needle is held open during acceleration.

In preferred embodiments of the invention, however, the apparatus is provided with additional control means for effecting predetermined or calibrated changes in the setting of the linkage. This control means may be disposed in a convenient location for manipulation by the centrifugal attendant whereby to select at will any desired rate of acceleration within a wide range for which the turbine may be designed. Furthermore, I have also provided automatic timing mechanism in association with the acceleration control system so that the centrifugal may be caused to accelerate at a predetermined rate during a part of each cycle and thereafter to change automatically to a different rate of acceleration, the time interval at which such change takes place and also the rate of acceleration prior thereto being susceptible to adjustment at the will of the centrifugal attendant. In embodiments such as these, changes in the setting of the servomotor linkage preferably are obtained by changing the position of one of the articulation points or pivots of the linkage.

The brake drum of the apparatus preferably is secured to the upper end of the turbine drive shaft, with the cooperating brake bands or shoes connected for activation by means of hydraulic cylinders or the like. Since the opening of the turbine nozzle to start and drive the machine and also the application of the brake to stop the machine take place in response to fluid or hydraulic pressure, the whole of the starting and stopping operations of the centrifugal may be controlled through the opening and closing of appropriate control valves, and these control op-

erations may be performed by operation of a single lever, either manually or automatically in response to suitable timing mechanism that may be provided to time and control automatically the stopping of the machine at the end of each cycle of operation. As indicated thereafter, the timer to be employed for automatic variation of the acceleration rate of the machine may be part of a timing mechanism common to the timer employed to stop the machine at the end of each operating cycle.

The foregoing and other objects, features and advantages of my invention will become more apparent from the following description of an illustrative embodiment thereof, when considered in connection with the accompanying drawings. It is to be understood, however, that the new features and combinations which I have invented are defined particularly in the appended claims and that the same may be embodied in various forms and arrangements of apparatus without restriction to the illustrative embodiment. In the drawings,

Figure 1 is a front elevation showing an assembly of the illustrative embodiment with the centrifugal spindle and basket broken away.

Figure 2 is a plan view of the apparatus of Figure 1, showing the brake assembly and parts of the turbine control.

Figure 3 is a vertical section through the centrifugal and turbine assembly, along line 3—3 of Figure 2.

Figure 4 is an enlarged vertical section substantially along line 4—4 of Figure 2.

Figure 5 is a horizontal section substantially along line 5—5 of Figure 4, showing details of the governor construction.

Figure 6 is an enlarged horizontal section through the turbine nozzle and part of the water housing.

Figure 7 is a vertical section substantially along line 7—7 of Figure 6.

Figure 8 is a side elevation showing parts of the turbine nozzle and of the control linkage connected therewith.

Figure 9 is an end elevation of the structure shown in Figure 8.

Figure 13 is a section along line 13—13 of Figure 11, showing detail construction.

Figure 14 is a vertical section substantially along line 14—14 of Figure 11, and

Figure 15 is a plan view substantially along line 15—15 of Figure 11.

Referring now to details of the illustrative embodiment, particularly to Figure 3, the assembly includes a suspended centrifugal spindle 10 carrying the usual perforate basket 12 at its lower end for rotation within a stationary casing or curb 14. The spindle 10 is suspended from a gyratory head 16 of any suitable construction, the illustrated head being similar to that disclosed in United States Patent No. 2,219,875. The head is supported from a stationary hanger 18. The spindle is adapted to swing or gyrate about a center located substantially at point A, where it is connected through a flexible coupling 20 with the lower end of a vertical drive shaft 22 to which is secured a Pelton wheel 24, of well

known form. Surrounding the wheel 24 is a water housing 26, the base of which rests upon conventional centrifugal framework B. In the illustrated embodiment, the hanger 18 is connected directly to the base of the housing 26, as at 28.

Secured to the upper and lower parts of housing 26 are bearing supports 30 and 32, respectively. Bushings 31 and 33, respectively, within these supports embrace upper and lower parts of the 10 drive shaft 22 and hold the shaft for rotation about a fixed vertical axis. To the upper end of shaft 22, above support 30, there is keyed a brake adaptor 36 having an annular brake drum 38 secured thereto. The upper end of adaptor 36 has a flared hollow wall at 40 to provide a chamber accommodating a speed governor unit 42, hereinafter to be described.

The water housing 26 is provided with a nozzle 44 for directing a water jet against the buckets 25 of the Pelton wheel 24, and also with an outlet pipe 46 for discharging water from the housing. A tube 48 vents air or vapors from the housing.

The turbine nozzle, as shown particularly in Figure 6, includes the nozzle body 50 having a replaceable, wear-resistant seat 52 therein to define the jet opening and having a tubular section 54 for the admission of water under pressure to drive the Pelton wheel. A needle 56 is carried by a reciprocable needle shaft 58 and is adapted normally to be held in a position closing the nozzle opening by means of a compression spring 60 which bears against the outer end of a plunger 62 secured to the needle shaft. This plunger, together with an inner end ring 64 thereof, serves as a piston which works in a cylinder 66 defined by the inner wall of a sleeve 68 secured to and constituting an extension of the nozzle body. A tube 70 (Figure 7) is provided to admit fluid under pressure into cylinder 66, and an outlet tube 72 is provided for relieving the pressure of such fluid under circumstances hereinafter described. Spring-loaded packings 74 and 76, respectively, are provided on the plunger and at the inner end of the cylinder to seal the latter against the escape of the pressure medium admitted through tube 70. It will be apparent that when water, oil or other fluid under sufficient pressure is admitted to the cylinder 66, the plunger will be caused to move outwardly against the resistance of the spring 60, with the result of moving the needle shaft and moving needle 56 away from closed position to allow a water jet to pass through the nozzle opening and press against the buckets 25 of the Pelton wheel.

The brake mechanism of the apparatus (Figures 1 and 2) includes two oppositely disposed arcuate brake shoes 80, each having a suitable brake lining 81 and being arranged to be forced into frictional engagement with the outer surface of the brake drum 38. Extending vertically from the upper end of the water housing 26 are two oppositely disposed stationary adaptor brackets 82 from which the brake mechanism is supported. These are joined together by a top plate 83 extending across and in spaced relation to the end of wall 40 (Figure 4). One end of each brake shoe is buckled to a bracket 82 through articulated links 84. The other end of each brake shoe is connected to the end of a brake plunger 86 70 having at its outer end a piston 88 reciprocable in a cylinder 90 that is swivelled to a part 92 integral with the corresponding adaptor bracket. A compression spring 94 in each brake cylinder normally urges the corresponding piston to a 75

position in which the brake shoe connected therewith is held out of engagement with the brake drum. Each cylinder, however, has a fluid conduit 96 opening into its outer end, so that upon admission of fluid pressure into the cylinder through this conduit the piston 88 will be moved forwardly against the resistance of spring 94 and the brake linings therefor will be forced against the brake drum so as to retard rotation of the machine.

In the illustrated arrangement the fluid conduits 96 for the two brake cylinders stem from a common tube 97 that is connected with a valve 98 in a valve box 200 (Figures 1, 10, 11, 14 and 15). The inlet tube or conduit 70 for the needle cylinder 66 is connected with a valve 99 in the same box. Each of the valves 98 and 99, as shown, is a three-way valve having a double valve seat 202 in which a stem 204 with corresponding seats operates. Each stem has a head 206 thereon and normally is held in its upper position by a spring 208. A valve shaft 212 extends across the heads 206 and carries eccentrics or cams 213 and 214 which are arranged in different positions so as to engage and hold the respective heads and valve stems in their lower positions in certain settings of the shaft. Shaft 212 has a squared portion 215 in engagement with a leaf spring 216, so that the leaf spring will hold the shaft in any of at least three settings.

The box 200 is secured by a bracket 218 to the back of a control housing 220, and an actuating shaft 222 extending through this housing is coupled to the valve shaft 212, as by means of a flexible coupling 224. A handle 226 is provided on the front end of shaft 222 by which to move the latter to any of three positions. When the handle is moved to the position of Figure 10 it starts the machine; when moved to the extreme left it stops the machine; and its vertical position is a neutral position in which neither the turbine nozzle nor the brake is active. This functional control is obtained as follows:

Hydraulic pressure is applied to the lower seat 45 of each of valves 98 and 99 from a water inlet 210. With the valves in neutral position, both valve stems 204 are held up by their springs 208, and water flow is blocked off at the lower valve seats. When the handle 226 is turned to start 50 position, the stem of valve 99 is lowered by cam 214 and the lower seat of this valve is opened while the upper seat is closed, valve 98 remaining unaffected. Water then flows into the body of seat 202, through a bore 227, through a small 55 gauge hole 228 in an adjustable throttle device 229 and thence into tube 70 and the nozzle cylinder 66. The gauge hole 228 limits the water flow to the nozzle cylinder in order that a speed control valve, hereinafter to be described, will work more efficiently. When handle 226 is turned back to neutral position the stem of valve 99 returns to its original position with its lower seat closed and its upper seat opened, so that water in the nozzle cylinder 66 then becomes free to flow back 60 through the valve and to escape through a drain pipe 211, thus allowing the nozzle needle 56 to close under the influence of spring 60.

A similar action takes place when handle 226 is turned to its stop position, except that valve 99 remains closed and valve 98 is opened so as to establish a pressure connection between a water inlet 210 and the tube 97 which transmits the pressure into the brake cylinders 90. In this condition of actuation, therefore, the brake is applied and the turbine nozzle is closed, which

brings the machine to a stop or keeps it from rotation. When the handle is again moved away from the stop position, the water in the brake cylinders becomes free to flow back through valve 98 and pass off through the drain pipe 211, whereupon the brake shoes are released by the action of the springs 94.

As seen in Figures 3 and 4, the speed governor 42 is fixed to the top of the turbine drive shaft by means of a horizontal plate 43 which is bolted to the upper end flange of wall 40, as at 44, so as to permit removal of the governor as a unit. From plate 43 a cylindrical casing 45 extends downwardly into the chamber enclosed by wall 40, and carries at its lower end hubs 100 in which are journaled oppositely disposed horizontal shafts 102 for governor weights 104 that have an angled form substantially as shown in Figure 4. These weights include hubs 105 articulated on the shafts 102, vertically extended weight arms 106 and inwardly extended arms 107 having rounded ends 108 which bear against the lower face of a plug 109 at the lower end of a non-rotary governor shaft or actuating member 110. This shaft is supported in ball bearings 111 at the lower end of casing 45, and the outer races of these bearings are fitted into the lower end of a sleeve 112 which surrounds the governor shaft and is movable vertically therewith in casing 45. One or more compression springs 114 and 115, confined within casing 45, bear at one end against the lower end of sleeve 112 and at their upper end against a nut 116 which is adjustably threaded in the upper end of casing 45 and adapted to be set in any position of adjustment by means of a set screw 117. The governor chamber provided by wall 40 of the brake drum adaptor has a plate 118 in its bottom to form an oil seal, which allows the chamber to hold enough oil to keep the weight shafts 102 immersed in oil when the machine is not in rotation. When the machine rotates, this oil moves outward under centrifugal force and forms a wall against the inner face of the wall 40.

The upper portion of the governor shaft 110 is squared, as at 120, to slide vertically, but not to rotate, within an opening provided therefor in a stationary cap 122 in the top plate 83. It will be apparent that the compression springs 114 and 115 exert a certain downward pressure on the governor shaft which tends to hold the weight arms 106 in vertical position. When, however, the machine attains a definite speed of rotation the centrifugal force of the weight arms 106 becomes great enough to overcome the compression of these springs, whereupon the weight arms swing outwardly, as to dotted line position of Figure 4, and cause vertical movement of the governor shaft 110. The speed of rotation at which this shifting of the governor takes place may be varied by changing the governor springs 114 and 115, or to a certain extent by changing the setting of the nut 116 so as to vary the compression of particular springs.

Secured to the top plate 83 in proximity to the governor 42 is a speed control or needle valve 130 having a valve seat 132, a valve needle 134 adapted to close a restricted opening through said seat, and chambers 136 and 138 on the lower and upper sides, respectively, of said seat. The needle 134 is carried by a reciprocable plunger 135, and a compression spring 137 normally holds the plunger downward with the needle in closed position. The outlet tube 72 from the nozzle cylinder 68 extends to a point of connection with 75 the nozzle opening during the period when the

the lower chamber 136. A drain tube 139 extends from the upper chamber 138 to a position where it may discharge into the water housing 28. Therefore, assuming that hydraulic pressure in the nozzle cylinder 68 is active to hold the needle 56 away from closed position, when the needle 134 is lifted from its seat there necessarily will be a release of pressure in cylinder 68 through tube 72 and the speed control valve, and when this occurs the compression spring 60 of the turbine nozzle may move the needle 56 toward its closed position, thereby reducing the size of the water jet and, consequently, the torque of the turbine.

Actuation of the speed control valve so as to effect such a reduction of pressure in the nozzle cylinder is accomplished as follows: A control rod 140 extends at one end into the valve plunger 135 and at its other end is articulated at 142 to the end of a lever arm 144. Between its ends rod 140 passes over a rounded end 145 of the governor shaft 110. This rod constitutes an element of a servomotor linkage (Figures 1 and 4) which, besides arm 144, includes an arm 146 movable with the latter on a fixed shaft 147, a connecting rod 148 articulated at its upper end to the end of arm 146 and at its lower end to the end of a lever arm 149 that is movable around a pivot 150, and an arm 151 integral with arm 149 and connected with the outer end of the needle shaft 58 through a yoke 152 and pivots 153. The connecting rod 148 preferably is provided with adjustable threaded elements 154 by which to vary its length.

With this arrangement, assuming pivot 150 to be in a fixed position and the nozzle needle to be open with the machine accelerating, when the predetermined speed for which the governor has been set is reached by the machine, the governor shaft or actuating member 110 will rise, engage the control rod 140 at point D and thereupon move the plunger 135 and needle 134 of the speed control valve to a position allowing the escape of water from cylinder 68 through the restricted orifice of the needle valve seat 132. When this occurs, the spring 60 of the turbine nozzle will move the nozzle needle 56 toward closed position. Such movement of needle 56 and needle shaft 58, however, will necessarily move the servomotor linkage to a different position and thus raise the articulation point 142. The raising of point 142 thereupon allows the valve needle 134 to be moved to a certain extent toward closed position by means of spring 137. Consequently, any equilibrium condition becomes established which maintains the speed control valve needle 134 at a certain clearance, which in turn maintains a certain pressure condition in the nozzle cylinder 68 and therefore keeps the nozzle delivering the amount of power required to run the machine at its predetermined top speed.

It also will be evident that the setting of the servomotor linkage determines the extent to which the nozzle needle 56 may move away from closed position in response to pressure of fluid in cylinder 68, and therefore that the setting of this linkage determines the size of the water jet and the torque or accelerating characteristic of the turbine. This setting may be varied by adjusting elements 154 so as to change the length of the connecting rod 148. Thus it becomes possible to change the torque or accelerating characteristic of the centrifugal by changing the length of the connecting rod, for that controls

governor is not active and thereby controls the pressure of the water jet against the Pelton wheel.

As mentioned hereinabove, I preferably provide additional control means for calibrating the setting of the acceleration control system and placing it under convenient manual or automatic control. For example, the pivot 150 for the lever arms 149 and 151 of the servomotor linkage is carried by arm 160 of a lever fulcrumed on a fixed pivot 162. Another arm 164 of the same lever is pivotally connected with the upper end of a rod 166 and normally is urged in a clockwise direction with respect to pivot 162, as by means of a spring 168. The lower end of rod 166 (see Figures 10 and 12) is articulated to an arm 169 keyed to a shaft 170. In spaced relation to arm 169 and fixed to the same shaft is a dog 172 which is arranged to bear at its end against the periphery of a rotary cam 174. Cam 174 is mounted on a shaft 176 extending across the housing 220, and at the forward end of shaft 176 there is a dial 178 which may be turned so as to turn cam 174, change the elevation of the end of dog 172, and thereby change the position of the pivot 150 constituting part of the servomotor linkage. Such changes obviously result in corresponding changes in the setting of the linkage and in the maximum extent to which the nozzle needle may move away from closed position in response to hydraulic pressure in cylinder 66.

The periphery of the cam 174 extends spirally from a low point to a high point where there is a radial drop back to the low point, as seen in broken lines in Figure 10. The dial 178 is marked with graduations which correspond to different elevations of the cam and therefore to different acceleration rates of the machine. A wing screw 180 may be set to hold the cam shaft 176 and cam 174 in any desired position of angular adjustment.

In addition, it may be desired under certain circumstances to provide for a quick change in the accelerating power of the turbine without changing the setting of the dial 178, as when it is desired to accelerate the centrifugal at a predetermined slow rate during the first part of a cycle and to change its acceleration to the maximum rate within the turbine power before the machine reaches its top speed. This may be accomplished manually as follows: Cam 174 is mounted on shaft 176 through a sleeve 182 against which bears a compression spring 184, so as normally to hold the cam beneath the end of dog 172. The cam and cam shaft, however, are free to slide axially against the resistance of spring 184, there being a splined connection at 185 with a bushing 186 which carries the dial 178. A yoke 188, mounted freely on shaft 170, embraces a groove 189 in sleeve 182 (Figure 12), so that forward movement of this yoke results in an axial shifting of cam 174 away from its normal position beneath the dog 172. Such movement of the yoke may be effectuated at will by forward movement of a handle 190 loosely carried on shaft 170, which handle acts through a detent 192 to swing the yoke. When this occurs, the spring 168 acting on the lever arm 164 causes the dog 172 to drop and causes the nozzle needle 56 to move to its maximum open position. To restore the cam 174 to a position beneath the dog 172, the handle 190 is provided with a detent 194 that engages and lifts dog 172 on the backward stroke of the handle, thereby allowing spring 168 to return the cam to its original position.

In order to cool the brake drum 38 so as to prevent overheating thereof and excessive wear-

ing of the brake linings 81, the brake is provided with a suitable water cooling system, for example of the type disclosed and claimed in United States Letters Patent No. 2,096,341. An inlet pipe 230 (Figure 1) is provided to convey cooling water into the drum 38, where it forms an annular wall against the inside of the drum during rotation of the machine. Pipe 230 leads from a spring-closed valve 232. When the machine is not running the water within the drum falls and is retained in the receptacle formed by the drum 38 and the brake adaptor 36. Excessive water is drawn off during operation of the machine through a discharge pipe 234, as shown in said Patent No. 2,096,341. The valve 232 is adapted to be opened when the machine starts in operation and to be closed at the end of each operating cycle in order to keep water from overflowing the receptacle inside of drum 38. This operation may be obtained, for example, by means of a detent 236 on a lever 240 which is connected with the actuating handle 226 through a link 238. As seen in Figure 1, movement of handle 226 to the right, or the starting position, will result in the opening of valve 232, and when lever 226 rests in its neutral or stop position the cooling water valve is kept closed by its spring.

The foregoing description of the illustrated embodiment will indicate the construction and manner of operation of this embodiment when operated entirely under manual control. Assuming that the apparatus is being used for the purging of sugar massecuite or the like, the attendant may set the dial 178 at a graduation corresponding to the acceleration rate desired at the start of the cycle and may then load the basket 12 with a charge of the mixture undergoing treatment. After the loading operation, the attendant simply turns handle 226 to the starting position, whereupon water under pressure passes into the nozzle cylinder 66 from valve 99 and the machine starts accelerating at the predetermined rate, with the brake in off position. If desired, the machine may be allowed to accelerate to top speed at the rate indicated by the setting of dial 178, or at any desired interval during the acceleration the handle 190 may be pulled forwardly so as to establish the maximum nozzle opening and hence the maximum accelerating power of the turbine. When the machine attains the top speed for which the governor has been set, the governor shaft 110 moves so as to shift the servomotor linkage, which opens the speed control valve 130 and establishes an equilibrium condition holding the machine at its predetermined speed. When the desired period of operation has expired, the attendant may move the handle 226 to its extreme left position, whereupon the turbine nozzle is closed by spring 60 and water pressure is applied to the brake cylinders 90 through valve 98 to stop the machine.

In addition to these provisions for manual control of the operations, however, the control system is provided with an automatic timing mechanism 250 which functions at the end of a predetermined but variable period to stop the machine automatically and also, if desired, to shift the acceleration control at a predetermined but variable interval after the start of each cycle. This timing mechanism is mounted adjacent to housing 220, and its casing 252 may provide support for the cooling water valve 232 hereinabove described. In construction and operation the mechanism is similar to that which is disclosed in United States Letters Patent No. 1,956,539 of

11

Eugene Roberts. Extending within the housing 252 is a timer shaft 254 which carries a timer head 256 at its outer end. A saw-tooth clutch (not shown) within housing 252, and suitable gears 258, are adapted to connect the timer shaft 254 for rotation with a parallel drive shaft 260 that revolves at a constant speed. The lever 240 connected with handle 226 operates to engage the timer clutch when handle 226 is moved to starting position, thereby causing a slow counterclockwise movement of the timer head 256 away from its initial or zero position. A torsion spring 262 connected with the timer shaft functions to return the head to its initial position when the clutch within housing 252 is disengaged, which occurs whenever handle 226 is moved away from the starting or running position.

The timer head 256 includes a plurality of adjustably related timer discs, such as 264 and 266. These discs may be set in any desired relative position by pulling and manipulating knobs 268 on the face of the timer head, as disclosed in said Patent No. 1,956,539. The discs 264 and 266 carry radial fingers 265 and 267, respectively, which act to shift the acceleration control and to cause a shifting of the control shaft 222 at predetermined but variable intervals after the start of each cycle.

Finger 267 acts on the acceleration control system by engaging a detent 280 carried on a radial arm 281 that is connected with a sleeve 282 from which the yoke 188 is supported. It will be evident that when finger 267 contacts and moves detent 280, a clockwise movement of arm 281 and yoke 188 occur so as to shift the cam 174 from beneath the end of dog 172. This of course establishes the maximum opening of the nozzle needle and causes the machine to accelerate at full power. The time when this occurs is varied by varying the initial setting of disc 266 and finger 267.

Finger 265 acts to stop the machine automatically in the following manner: The control shaft 222 has a disc 290 loosely mounted thereon which is urged in a clockwise direction, as viewed in Figure 10, by means of a torsion spring 292. A pin 294 integral with disc 290 extends parallel to shaft 222, and a radial arm 296 keyed to said shaft is adapted to engage and to be engaged by said pin. The disc 290 has a radial shoulder 298 which is formed to abut against the end of a lever arm 300. Another arm 302 of the same lever extends upwardly to a point where a transverse end 304 thereof will lie in the path of turning movement of finger 265. Therefore, when handle 226 is turned to the right to start the machine, arm 296 engages pin 294 on disc 290 and moves the disc until the end of arm 300 engages behind the disc shoulder. When a predetermined period of time, as determined by the initial setting of finger 265, has expired, this finger engages the end 304 of arm 302 and lifts this arm so as to free the end of arm 300 from the disc shoulder. Thereupon the torsion spring 292 turns the disc in clockwise direction, causing pin 294 to abut against arm 296 and turn the control shaft and handle 226 to their stop position. This, as previously described, cuts off hydraulic pressure to the nozzle cylinder and establishes pressure in the brake cylinders so as to stop the machine.

It will be understood that the control mechanisms shown in Figure 10 or other equivalent mechanisms may be mounted in any desired position for convenient manipulation by an attendant of the centrifugal. While I have shown

12

them as being supported from the framework B, this has been done merely for convenience of illustration. Also, the timing control mechanisms may be provided with additional timers and motivating systems to be actuated thereby for controlling the operation of sprayers and syrup separators in centrifugals provided with such devices, as will be readily understood by those skilled in the art.

10 It also will be understood, as hereinbefore mentioned, that each of the several new features and combinations of my invention, either alone or in combination with other new features here disclosed, may be embodied in various different forms of apparatus without restriction to the illustrated embodiment. I therefore desire that my invention be accorded a scope fully commensurate with its contributions to the art, as intended to be set forth in the appended claims.

20 I claim:

1. In a centrifugal machine comprising a stationary hanger supporting a suspension head and a gyratory basket-carrying spindle suspended from said head, the combination therewith of an impulse turbine above said hanger comprising a vertical drive shaft, an impulse wheel secured to said shaft intermediate its ends, a nozzle for directing a fluid jet against said wheel, said nozzle having a movable needle to govern the size of said jet, and a stationary housing for fluid surrounding said wheel, a flexible coupling connecting the lower end of said shaft for rotation with said spindle, said shaft extending above said housing and having a hollow extension upon its upper end, a speed governor secured to and located within said extension, and means movable by said governor and operating upon said needle for controlling the position of said needle.

40 2. In a suspended, gyratory centrifugal having a basket-carrying spindle and a hydraulic turbine connected with said spindle for driving the centrifugal, the combination of a vertical turbine shaft mounted in fixed bearings above said spindle, a flexible coupling connecting said shaft with said spindle, an impulse wheel secured to said shaft, a stationary water housing surrounding said wheel intermediate the ends of said shaft, a nozzle for directing a water jet against said wheel and having an adjustable needle therein for controlling the size of the jet, a speed governor secured for rotation with said shaft, and needle control means responsive to said governor for causing movement of said needle to reduce the size of said jet when the centrifugal has reached a predetermined speed.

50 3. In centrifugal apparatus comprising a suspended gyratory spindle and a centrifugal basket carried at the lower end of said spindle, the combination therewith of a hydraulic turbine including a fixedly mounted turbine shaft located above and connected for rotation with said spindle, an impulse wheel secured to said shaft, a nozzle for directing a water jet against said wheel, said nozzle having an adjustable needle therein for varying the nozzle opening, a stationary water housing surrounding said shaft for collecting water discharged from said wheel, a speed governor connected for rotation with said shaft, and a servomotor linkage connected with said needle and associated with said governor for movement thereby so as to move said needle toward closed position when the centrifugal approaches a predetermined speed.

70 4. In a machine comprising a rotary driven shaft and a hydraulic turbine connected to drive

the same including an impulse wheel, a water housing surrounding said wheel and a nozzle for directing a water jet against said wheel, a nozzle needle carried by a movable needle shaft within said nozzle for varying the nozzle opening, spring means acting on said shaft to urge said needle to closed position, a cylinder having a piston therein secured to said shaft and adapted to be actuated by fluid under pressure to move said needle away from closed position against the resistance of said spring means, fluid inlet and outlet tubes connected with said cylinder, a valve for admitting fluid under pressure to said inlet tube, and control means including a needle valve remote from said nozzle and connected with said outlet tube for reducing the pressure of fluid in said cylinder to control the speed of said turbine, said needle valve having a spring normally urging the same to closed position, a speed governor connected for rotation with said driven shaft, a shiftable element moved by said governor to a predetermined position in response to a predetermined high speed of said driven shaft, and linkage connected with said needle valve and positioned to be engaged and moved by said element, when the latter is moved to said predetermined position, for opening said needle valve against the resistance of said spring.

5. In a machine comprising a rotary driven shaft and a hydraulic turbine connected to drive the same including a vertical driving shaft having an impulse wheel secured thereto, a water housing surrounding said wheel and a nozzle for directing a water jet against said wheel, a movable nozzle needle for varying the nozzle opening, spring means urging said needle to closed position, fluid pressure responsive means for overbalancing the force of said spring means and moving said needle away from closed position, a control system for admitting or restraining a supply of fluid under pressure to or from said pressure responsive means, and a speed control system operative automatically when the driving shaft has attained a predetermined speed for regulating the position of said needle, said speed control system including a normally closed control valve for relieving fluid pressure on said pressure responsive means, a speed governor connected for rotation with said driving shaft, a shiftable element movable by said governor to a predetermined position in response to a predetermined high speed of rotation of said driving shaft, a servomotor linkage connected with said control valve and positioned to be engaged and moved by said element, when the driving shaft has attained said predetermined speed, so as to open said control valve and cause closing movement of said needle under the force of said spring means, said linkage having connections with said needle so that closing movement of said needle displaces said linkage with respect to said element and moves said control valve to maintain substantially said predetermined speed.

6. In a machine comprising a rotary driven shaft and a hydraulic turbine connected to drive the same including a driving shaft mounted in fixed bearings and having an impulse wheel secured thereto, a water housing surrounding said wheel and a nozzle for directing a water jet against said wheel, a movable nozzle needle governing the size of the nozzle opening, yieldable means normally holding said needle in closed position, fluid pressure responsive means for overbalancing the force of said yieldable means and moving said needle away from closed position, a

normally closed control valve for relieving fluid pressure on said pressure responsive means, a servomotor linkage connected with said needle to limit the opening movement thereof and to be moved by closing movement thereof, said linkage including a member also connected with said control valve and operable to move the same, a speed governor connected for rotation with said driving shaft, a shiftable element moved by said governor, when the driving shaft has attained a predetermined speed, a predetermined position where said element engages and moves to said linkage member so as to open said control valve, said linkage being operative thereafter in response to movements of said needle and said element to vary the positions of said control valve and needle so as to keep the driving shaft rotating substantially at said predetermined speed, and adjustable means for varying the setting of said linkage so as to vary the extent of opening movement of said needle and thereby control the accelerating rate of the shafts.

7. In a suspended gyratory centrifugal machine having an impulse turbine connected therewith to drive the same, said turbine having a driving shaft, an impulse wheel thereon and a nozzle for directing a water jet against said wheel, the combination therewith of starting control means connected with the turbine nozzle and arranged to be actuated manually by an attendant for opening the nozzle, a speed control system including a governor connected with said shaft and linkage connected with said nozzle and rendered operative by said governor when the machine has attained a predetermined speed for reducing the nozzle opening so as to keep the machine running at substantially said predetermined speed, and acceleration control means connected with said linkage and having manually operable means to adjust the setting thereof for predetermining and controlling the size of the nozzle opening before the machine has attained such speed whereby to control the rate of acceleration of the machine.

8. In a suspended gyratory centrifugal having an impulse turbine connected therewith for driving the same, said turbine including a nozzle having a needle movable to vary the nozzle opening, the combination therewith of starting control means connected with the turbine nozzle and arranged to be actuated manually by an attendant so as to open said nozzle and start the machine, variable acceleration control means including linkage connected with said needle and arranged to be set manually at any of a plurality of available settings so as to govern the size of the nozzle opening during the acceleration of the centrifugal, timing mechanism including an adjustable rotary timer to be started in rotation upon actuation of said starting control means as aforesaid, and means connected with said linkage and shiftable by said timer element after a predetermined period of its rotation for automatically changing the setting of said acceleration control means during the acceleration of the centrifugal.

9. In a suspended gyratory centrifugal having an impulse turbine connected therewith for driving the same, said turbine including a nozzle having a needle movable away from closed position to vary the nozzle opening, the combination therewith of fluid pressure responsive means at the nozzle for so moving the needle, a fluid pressure system connected with the nozzle including a control valve adapted when opened to admit fluid under pressure to said pressure responsive means,

manually operable starting means for opening said valve, automatically operable timing mechanism adapted to be started upon the operation of said starting means and including at least two timers capable of independently adjustable time settings, means rendered active by one of said timers for closing said valve at the end of a predetermined but variable period after the operation of said starting means, adjustable acceleration control means connected with said needle for governing the nozzle opening during the acceleration of the centrifugal, and means connected with said acceleration control means and actuated by another of said timers for automatically changing the setting of said acceleration control means at the end of a predetermined but variable period after the operation of said starting means.

10. In a suspended gyratory centrifugal having an impulse turbine connected therewith for driving the same, said turbine including a nozzle having a needle movable away from closed position to vary the nozzle opening, the combination of means to impose a yielding resistance against such needle movement, fluid pressure responsive means for so moving the needle, a starting valve adapted when opened to admit fluid under pressure to said pressure responsive means, a control valve adapted when opened to reduce the pressure of such fluid on said pressure responsive means, manually operable control means for opening and closing said starting valve, an automatic speed control system including a speed governor connected for rotation with the centrifugal and a servomotor linkage connected respectively with said needle and said control valve and associated with said governor for actuation thereby so as to open said control valve when the centrifugal has attained a predetermined speed, and adjustable means connected with said linkage for governing the size of the nozzle opening from the opening of said starting valve until the opening of said speed control valve, whereby to govern the rate of acceleration of the centrifugal.

11. In a suspended gyratory centrifugal having an impulse turbine connected therewith for driving the same, said turbine including a nozzle having a needle movable away from closed position to vary the nozzle opening, the combination of means to impose yielding resistance against such movement, fluid pressure responsive means for so moving the needle, a starting valve adapted when opened to admit fluid under pressure to said pressure responsive means, a control valve adapted when opened to reduce the pressure of such fluid on said pressure responsive means, manually operable control means for opening and closing said starting valve, an automatic speed control system including a speed governor connected for rotation with the centrifugal and a servomotor linkage connected respectively with said needle and said control valve and associated with said governor for actuation thereby so as to open said control valve when the centrifugal has attained a predetermined speed, a variable acceleration control system connected with said linkage for controlling the setting of said linkage so as to govern the size of the nozzle opening during acceleration of the centrifugal, timing mechanism arranged to be started in operation in definitely timed relation to the opening of said starting valve and including at least two timers each capable of variable time settings, means associated with said control means and one of said timers for actuation by the latter so as to close said starting valve at the end of a predetermined but variable period

after the opening thereof, and means associated with said acceleration control system and another of said timers for actuation by such other timer for changing the setting of said linkage so as to change the size of the nozzle opening at the end of a predetermined but variable period after the opening of said starting valve.

5 12. A combination as described in claim 11, and a manually operable member connected with said 10 acceleration control system for varying the setting of the latter at will.

13. In a machine comprising a rotary driven shaft and a water turbine for driving the same including a vertical drive shaft mounted in fixed 15 bearings and connected for rotation with said driven shaft, an impulse wheel secured to said drive shaft, a water housing surrounding said wheel and a nozzle for directing a water jet against said wheel, said nozzle having a needle 20 therein movable away from closed position to form the jet opening, fluid pressure responsive means for so moving the needle and means yieldably to urge the needle toward closed position, a speed governor mounted on the upper end of said 25 drive shaft, a non-rotary shiftable element moved by said governor to a predetermined position when said shaft has attained a predetermined full speed, a spring-closed needle valve disposed adjacent to said shiftable element and connected with 30 said fluid pressure responsive means so as, when opened, to reduce the pressure of fluid on the latter, and a servomotor linkage mounted for movement relative to two fixed pivots and connected with said nozzle needle beyond one of said pivots 35 so as to limit the size of the jet opening, said linkage being connected beyond the other of said pivots with said needle valve through an articulated rod disposed in the path of movement of said shiftable element so that said linkage is 40 moved by said element to open said valve when said element is moved to said predetermined position.

14. In a machine comprising a rotary driven shaft and a water turbine for driving the same including a vertical drive shaft mounted in fixed 45 bearings and connected for rotation with said driven shaft, an impulse wheel secured to said drive shaft, a water housing surrounding said wheel and a nozzle for directing a water jet against said wheel, said nozzle having a needle 50 therein movable away from closed position to form the jet opening means to impose yieldable resistance against such needle movement and fluid pressure responsive means for so moving the needle, a speed governor mounted on the upper end of said drive shaft, a non-rotary shiftable element moved by said governor to a predetermined position when said shaft has attained a predetermined 55 full speed, a spring-closed needle valve disposed adjacent to said shiftable element and adapted when opened to reduce the pressure of fluid on said fluid pressure responsive means, and a servomotor linkage mounted for movement relative to two fixed pivots and connected with said nozzle needle beyond one of said pivots so as to limit the size of the jet opening, said linkage being connected beyond the other of said pivots with said needle valve through an articulated rod disposed in the path of movement of said shiftable element so that said linkage is moved by said element to open said valve when said element is moved to said predetermined position, said linkage intermediate said pivots including connecting means 60 of adjustable length whereby to vary the setting

17

of the linkage and thereby the acceleration rate of the machine.

15. In a machine comprising a rotary driven shaft and a water turbine for driving the same including a drive shaft mounted in fixed bearings and positively connected with said driven shaft, an impulse wheel secured to said drive shaft, a water housing surrounding said wheel and a nozzle for directing a water jet against said wheel, said nozzle having a needle therein movable away from closed position to form the jet opening means to impose yieldable resistance against such needle movement, and fluid pressure responsive means for so moving the needle, a speed governor mounted on an end of said drive shaft, a non-rotary shiftable element moved by said governor to a predetermined position when said shaft has attained a predetermined full speed, a spring-closed needle valve disposed adjacent to said shiftable element and adapted when opened to reduce the pressure of fluid on said fluid pressure responsive means, a servomotor linkage mounted for movement relative to two fixed pivots and connected with said nozzle needle beyond one of said pivots so as to limit the size of the jet opening, said linkage being connected beyond the other of said pivots with said needle valve through an articulated rod disposed in the path of movement of said shiftable element so that said linkage is moved by said element to open said valve when said element is moved to said predetermined position, and acceleration control means capable of being set in various positions at the will of an attendant for varying the position of one of said pivots and thereby varying the setting of said linkage and the acceleration rate of the machine.

16. In a machine having an impulse turbine for driving the same, including a water nozzle for the turbine wheel having a needle movable to open position to start the machine, a movable linkage connected with said needle to govern the extent of its opening movement, and a variable controller connected with said linkage to establish the setting thereof, said controller comprising a dog connected with said linkage, a movable cam to determine the position of said dog, and a manually operable member to vary the setting of said cam.

17. In a machine having an impulse turbine for driving the same, including a water nozzle for the turbine wheel having a needle movable to open position to start the machine, a movable linkage connected with said needle to govern the extent of its opening movement, and a variable controller connected with said linkage to establish the setting thereof, said controller comprising a pivotally mounted dog connected with said linkage, a rotatable cam normally limiting movement of said dog, means urging said dog against said cam, manually operable means for turning said cam to vary the setting of said dog, and means for shifting said cam axially to free said dog from said cam.

18. In a machine having an impulse turbine for driving the same, including a water nozzle for the turbine wheel having a needle movable to open position to start the machine, a movable linkage connected with said needle to govern the extent of its opening movement, and a variable controller connected with said linkage to establish the setting thereof, said controller comprising a pivotally mounted dog connected with said linkage, a rotatable cam normally limiting movement of said dog, means urging said dog against said

18

cam, manually operable means for turning said cam to vary the setting of said dog, and means for shifting said cam axially to free said dog from said cam, said last-recited means including a rotary timer having an adjustable arc of rotation and a device operated by said timer so as to shift said cam after a predetermined but variable period of rotation of said timer.

19. In a machine having an impulse turbine for driving the same, including a water nozzle for the turbine wheel having a needle movable to open position to start the machine, a movable linkage connected with said needle to govern the extent of its opening movement, and a variable controller connected with said linkage to establish the setting thereof, said controller comprising a pivotally mounted dog connected with said linkage, a rotatable cam normally limiting movement of said dog, means for urging said dog against said cam, manually operable means for turning said cam to vary the setting of said dog, a spring normally holding said cam in alignment with said dog, a hand lever having means thereon for shifting said cam axially against said spring so as to free said dog when the lever is moved in one direction, and means operative when said lever is moved in the opposite direction for lifting said dog, whereby to allow return of said cam to its normal position.

20. In a centrifugal machine comprising a stationary hanger supporting a suspension head and a gyratory basket-carrying spindle suspended from said head, the combination therewith of an impulse water turbine above said head comprising a vertical drive shaft mounted in fixed vertical position in vertically spaced fixed bearings, an impulse wheel fixed to said shaft intermediate said bearings, a flexible coupling connecting the lower end of said shaft with the upper end of said spindle in said head, a hollow brake adaptor carrying a vertical brake drum and secured directly to the upper end of said shaft, said adaptor having a hollow axial extension open at the top and disposed at least partly within the confines of said drum, a stationary water housing surrounding said shaft and said wheel between said adaptor and said head, a water nozzle mounted on said housing for directing a water jet against said wheel, said nozzle having a movable needle to govern the size of said jet, and means including a speed governor unit secured to and located inside said extension and connections movable by said governor and operating upon said needle for controlling the position of said needle.

21. In a suspended gyratory centrifugal having an impulse turbine connected therewith for driving the same, the combination of a turbine nozzle having a needle movable away from closed position to establish the nozzle opening, fluid pressure responsive means for so moving the needle, a system for applying fluid pressure to said pressure responsive means, said system including a control valve adapted when opened to admit fluid under pressure to said pressure responsive means, manually operable starting means for opening said valve, timing mechanism including a timer adjustable to various time settings, manually operable means for starting said timing mechanism when said valve is opened, and means rendered active by said timer for closing said valve at the end of a predetermined but variable period of operation of said timing mechanism.

Certificate of Correction

Patent No. 2,402,496.

June 18, 1946.

JOSEPH HERTRICH

It is hereby certified that errors appear in the printed specification of the above numbered patent requiring correction as follows: Column 4, line 6, for "hereinafter" read *hereinafter*; column 8, line 53, for "any" read *an*; column 14, line 12, claim 6, strike out "to" and insert the same in line 11, same claim, after the word and comma "speed,"; and that the said Letters Patent should be read with these corrections therein that the same may conform to the record of the case in the Patent Office.

Signed and sealed this 3rd day of September, A. D. 1946.
